UNITED STATES PATENT OFFICE.

ARTHUR J. ADAMS, OF BAY CITY, MICHIGAN, ASSIGNOR TO THE FULTON COMPANY, OF BAY CITY, MICHIGAN, A CORPORATION OF MICHIGAN.

SERVICE-TABLE.

1,333,954.

Specification of Letters Patent. Patented Mar. 16, 1920.

Application filed November 12, 1917. Serial No. 201,499.

To all whom it may concern:

Be it known that I, ARTHUR J. ADAMS, a citizen of the United States, residing at Bay City, in the county of Bay and State of Michigan, have invented a new and useful Improvement in Service-Tables, of which the following is a specification.

This invention relates particularly to portable service-tables or tray-wagons; and 10 the primary object is to provide a structure of staunch construction and neat appearance, the structure being partially of knock-down construction and capable of being folded into compact form.

15 The invention is illustrated in its preferred embodiment in the accompanying drawings, in which—

Figure 1 represents a side elevational view of a service-table embodying my invention; Fig. 2, a front elevational view of the same; Fig. 3, a bottom view of the structure in collapsed form; Fig. 4, an edge elevational view, illustrating the manner in which the parts may be packed together for 25 shipment; Fig. 5, an enlarged broken sectional view, taken as indicated at line 5 of Fig. 2; Fig. 6, a broken sectional view showing the manner of equipping one pair of legs of the structure with casters; and Fig. 7, 30 a broken bottom plan view, illustrating a slight modification.

In the preferred embodiment, which is illustrated, the invention comprises an upper table, or tray, A; a lower table or tray B; a front standard, or pair of legs, C; a rear standard, or pair of legs, D; an axle E, equipped with wheels E¹, said axle E serving to support the front legs C; casters F for the legs D; an inclined brace or 40 reach G extending from the axle E to the rear portion of the lower table B; and a handle H connected with the rear end portion of the upper table A.

The table A may be of wood, or of any 45 other suitable material. The under surface of the table A is equipped at its front end with a cross-bar, or bracket bar, 1, having down-turned extremities 1^a, adapted to serve as pivot-lugs; and the under-surface 50 of said table is further equipped, at its rear end, with a similar bracket-bar 2, having down-turned extremities 2^a, adapted to serve as pivot-lugs.

The upper ends of the legs comprising the 55 standard C, are pivotally connected with

the front end of the table A through the medium of pivots 1^b, which extend through the upper ends of the legs and pivot ears 1^a.

The upper ends of the legs comprising the 60 standard D are pivotally connected with the rear end of the table A through the medium of pivots 2^b, which extend through the upper ends of the legs and through the pivot ears 2^a.

It thus appears that the pivots for the 65 legs are spaced a short distance below the table A. This enables the legs to be turned about the pivots 1^b and 2^b and brought into a plane parallel with the plane of the table A. 70

Both the front and the rear legs are integral or continuous, i. e., they are non-jointed, so that each pair of legs swings as a unit about the pivotal axis at the upper end of the pair. 75

The legs comprising the front standard C are equipped some distance above their lower ends with a table-support or bracket C¹; and the legs D comprising the rear standard are equipped some distance above 80 their lower ends with the table-support or bracket D¹. The braces or table-supports C¹ and D¹ are rigidly secured, respectively, between the members of each pair of legs, and brace the legs transversely. Upon these 85 supports, the lower table or tray B is demountably supported. The lower ends of each pair of legs are offset toward each other from the points 3 and 4 downwardly. The brackets C¹ and D¹ are attached to the 90 lower end portions of the legs, and extend upwardly a short distance above the points of offset 3 and 4, thus affording clearance for the table B, which rests upon the brackets. The bracket C¹ comprises a cross-bar 3^a having 95 down-turned arms 3^b which are riveted to the offset lower ends of the legs; and a brace member 3^c having a web portion secured by rivets to the intermediate portion of the cross-member 3^a and having inclined arms secured by rivets to the down-turned arms 3^b.

The bracket or table-support D¹ is of similar construction. It comprises a cross-member 4^a having downturned arms 4^b 105 which are riveted to the lower end portions of the legs D; and a brace-member 4^c of the same general configuration as the brace-member 3^c.

The legs C and D are preferably of tubu- 110

lar steel; and the chairs, or table-supports, C¹ and D¹, are readily formed of steel bars.

The lower surface of the table B is equipped near its extremities with cross-bars 5, which are secured to the table, as by means of screws 5^a. The bars 5 are provided near their extremities with downwardly struck, or offset, portions 5^b (Figs. 2 and 5), which accommodate screw bolts 5^c. Thus, 10 the table B is equipped at its end portions with downwardly extending threaded studs, which pass through perforations in the cross-members 3^a and 4^a of the chairs or table-supports C¹ and D¹. The parts are 15 secured together by means of wing nuts 6 threaded upon the studs.

The axle E is secured (Fig. 1) to the lower end portions of the legs C by means of brackets 7. The reach-member or brace G preferably 20 comprises a pair of bars 8 which cross each other diagonally and are secured together at the central point 8^a. The lower front ends of the bars 8 are pivotally connected with the axle E as indicated at 8^b. 25 The rear upper ends of the bars 8 are provided with perforations which receive the studs 5^c (Fig. 5) with which the bracket-bar 5 at the rear end of the table is equipped. Thus, the bolts which serve to secure the 30 rear end of the table B to the chair or table-support D¹ serve also to connect the rear ends of the reach-members with said support.

The wheels E¹ are detachably journaled 35 on the ends of the axle E, and may be removed at will. The lower ends of the legs D project some distance below the axle E, and are equipped with the casters F, which are preferably detachable as indicated in 40 Fig. 6.

In the construction which has been described, the legs C are more widely separated than are the legs D (see Fig. 2). In order that the upper ends of the legs C may 45 occupy the same longitudinal plane as the upper ends of the legs D, the upper ends of said legs C are offset inwardly, as shown in Fig. 2. This enables the bracket-bars 1 and 2 to be of the same length.

50 In the modification shown in Fig. 7, A¹ represents the upper table; C² represents one of the front legs; and D² represents one of the rear legs. In this construction the upper end of the leg C² is not offset, and the bracket-bar 1^c is lengthened and connected by a pivot 1^d with the upper end of the leg C².

It is desirable to have the members of 60 one pair of legs more widely separated than the members of the other pair of legs, in order that the one pair of legs may lie within the other pair in the folded condition of the structure. Obviously, this may be accomplished with or without offsetting the upper 65 ends of the legs C, as has been illustrated.

The handle H (Fig. 3) comprises a U-shaped member whose arms are connected, by bolts 9 with the rear cross-member of the table A, and by screws 10 with the table. If desired, the handle may be removed before the structure is crated. 70

When it is desired to place the structure in compact form for the purpose of crating or storing, the table B is removed from the chairs or table-supports C¹ and D¹ with 75 which the legs of the structure are equipped. This removal may be accomplished by removing the wing-nuts 6 and lifting the table B from the position shown in Fig. 1. This also disconnects the rear ends of the 80 reach-members 8, so that the reach G may be swung about the axle E and brought into position parallel with the legs C. The legs C may then be folded against the under-surface of the table A, which will also place 85 the reach G adjacent the under surface of said table. The legs D may then be folded into a plane parallel with the table. Previous to the folding operation, the wheels and casters may be removed; and, if desired, 90 the handle H may be removed. The parts may then be assembled in the manner illustrated in Fig. 4, it being understood that in the illustration they are left separated somewhat for clearness of understanding. This 95 enables the structure to be crated or wrapped, in compact form, for storage or shipment purposes.

When the structure is assembled in the condition shown in Figs. 1 and 2, it presents 100 a thoroughly rigid and staunch construction, which is of neat appearance, and which is thoroughly adapted to its purpose.

The foregoing detailed description has been given for clearness of understanding 105 only and no unnecessary limitations should be understood therefrom, but the appended claims should be construed as broadly as permissible in view of the prior art.

What I regard as new and desire to secure 110 by Letters Patent is:—

1. A structure of the character set forth comprising an upper table, a pair of upright rigid legs pivotally connected with the front portion thereof and adapted to swing rearwardly and upwardly to a position beneath the table, a pair of upright rigid legs pivotally connected to the rear portion of the table and adapted to swing forwardly and upwardly to a position beneath the table, and a lower table demountably secured to 115 said legs some distance above the lower ends thereof.

2. A structure of the character set forth comprising an upper table, a pair of upright rigid front legs pivotally connected with the front end of said table, a pair of upright rigid rear legs pivotally connected with the rear end of said table, wheels supporting 120 said front legs, the lower ends of the rear 125 legs being secured to the under surface of the table.

legs extending below the axes of said wheels and having means adapted to rest upon the floor, and a lower table demountably secured at its ends to said legs above the plane of 5 said wheels.

3. A structure of the character set forth comprising an upper table, an upright rigid front standard pivotally connected with the front end of said table and equipped with 10 wheels, an upright rigid rear standard pivotally connected with the rear end of said table and adapted to be supported on the floor, table-supports secured to said standards and located in a plane immediately 15 above said wheels, and a lower table demountably carried by said table supports.

4. A structure of the character set forth comprising an upper table, a front pair of upright rigid legs pivotally connected with 20 the front end of said table and equipped some distance above their lower ends with a table-support, an axle connected with the lower end of said legs, wheels mounted on said axle, a rear pair of upright rigid legs 25 pivotally connected with the rear end of said table and adapted to be supported on the floor, a table-support carried by said rear legs and disposed above the plane of said wheels, a lower table demountably secured 30 to said supports, and a reach connecting said axle with the rear portion of said structure in the vicinity of the rear end of said lower table.

5. A structure of the character set forth comprising an upper table, a front pair of 35 upright rigid legs pivotally connected with the front end of said table, a rear pair of upright rigid legs pivotally connected with the rear end of said table and of greater 40 length than the front pair of legs, braces connecting the members of each pair of legs and affording table-supports located at an intermediate plane, a lower table demountably carried by said table-supports, wheels 45 connected with the lower ends of the front legs, and a handle connected with the rear end of the upper table.

6. A structure of the character set forth comprising an upper table, a pair of integral front legs pivotally connected therewith and equipped at their lower ends with 50 wheels, a bracket connecting the lower portions of said legs and affording a table-support disposed in a plane above said 55 wheels, a pair of integral legs pivotally connected with the rear end of said table and of greater length than the first-mentioned legs and a bracket connecting the lower portions of said second-mentioned legs and after 60 affording a table-support, a reach pivotally connected with the lower ends of the first-mentioned legs and detachably connected with said second-mentioned bracket, and a table demountably carried by said brackets.

7. A structure of the character set forth comprising an upper table, a pair of integral front legs pivotally connected therewith, a pair of longer integral rear legs pivotally connected with said table, wheels supporting 70 said front legs, a reach pivotally connected with the lower portions of the front legs and adapted to fold into a plane parallel with the front legs, a table supported by said legs in a plane above said wheels, and detachable connections for said second-mentioned table and the rear end of said reach. 75

8. A structure of the character set forth comprising an upper table, a pair of upright integral front legs pivotally connected 80 with the front end of said table and having rearwardly off-set lower end-portions, a table-supporting bracket connected with the lower portions of said legs and projecting above the points of off-set of said legs, a pair of longer upright integral rear legs 85 pivotally connected with the rear end of said table and having forwardly off-set lower portions, a table-supporting bracket connected with the lower off-set portions of 90 said second-named legs and projecting above the points of off-set, a lower table demountably carried by said brackets, and a pair of wheels connected with the lower ends of 95 said first-mentioned legs.

9. A structure of the character set forth comprising an upper table, a pair of substantially upright front legs pivotally connected therewith and having rearwardly off-set lower end portions, a table-supporting 100 bracket connected with the lower portions of said legs and projecting above the points of off-set of said legs, a pair of longer substantially upright rear legs pivotally connected 105 with said table and having forwardly off-set lower portions, a table-supporting bracket connected with the lower off-set portions of said rear legs and projecting above the points of off-set, a lower table demountably carried by said brackets, a pair of wheels 110 connected with the lower ends of said front legs, and a reach pivotally connected with the lower ends of said front legs and detachably connected with said second-named bracket. 115

10. A structure of the character set forth comprising an upper table, a pair of integral front legs pivotally connected to the front end thereof, an axle connected to the lower end of said legs, wheels mounted on said 120 axle, a pair of longer integral rear legs pivotally connected with the rear portion of said table and having their lower ends equipped with casters, a reach pivotally connected with said axle and having detachable 125 connection with the rear legs, and a handle connected with the rear portion of said table.

11. A structure of the character set forth

comprising an upper table, a pair of substantially upright integral front legs pivotally connected with the front end thereof and equipped some distance below the lower ends with a cross-bar, a pair of substantially integral rear legs pivotally connected with the rear end of said table and equipped some

distance below their lower ends with a cross-bar, a lower table equipped with depending threaded studs extending through perforations in said cross-bars, nuts on said studs, and a handle connected with the rear portion of said first-mentioned table. 10

ARTHUR J. ADAMS.
